UNITED STATES PATENT OFFICE

WILLIAM GREEN, OF GLENS FALLS, NEW YORK

DESIGN FOR A TRELLIS

Application filed February 2, 1931. Serial No. 38,512. Term of patent 7 years.

To all whom it may concern:

Be it known that I, WILLIAM GREEN, a citizen of the United States, residing at Glens Falls, in the county of Warren and State of New York, have invented a new, original, and ornamental Design for a Trellis, of which the following is a specification, reference being had to the accompanying drawing, forming a part thereof.

In the drawing, the figure is a view in perspective of a trellis showing my new design.

I claim:

The ornamental design for a trellis as shown.

WILLIAM GREEN.
